United States Patent Office

Des. 216,295
Patented Dec. 16, 1969

216,295

PACKAGING CONTAINER

James Alexander, Belleville, N.J., assignor to Scandia
Packaging Machinery Company, a corporation of New Jersey

Filed Apr. 16, 1968, Ser. No. 11,480

Term of patent 14 years

Int. Cl. D9—99

U.S. Cl. D9—191

FIG. 1 is a perspective view of a packaging container showing my new design;

FIG. 2 is a side elevational view;

FIG. 3 is a top plan view; and

FIG. 4 is a bottom plan view thereof.

I claim:

The ornamental design for a packaging container, as shown.
